UNITED STATES PATENT OFFICE.

CLIFFORD E. ALBERT, OF CINCINNATI, OHIO, ASSIGNOR TO THE UNITED STATES PLAYING CARD COMPANY, OF CINCINNATI, OHIO, A CORPORATION OF OHIO.

PLAYING CARDS.

Application filed June 21, 1926, Serial No. 117,334, and in Canada February 22, 1926.

My invention relates to playing cards and particularly to playing cards of the customary type, including conventional suit and value designations, and has for its object 5 so to place the indexes that the numbers and values of the cards in a given hand may readily be perceived even though such hand is not arranged by suits in the customary 10 manner, this application being a continuation in part of application 79,308, filed Jan. 5, 1926.

In the accompanying drawing, Fig. 1 is a face view of a hand of cards, for instance in a game of bridge whist, fanned in the 15 usual manner, and Fig. 2 is a face view of one of the cards of Fig. 1.

As clearly shown in the drawing, the indexes of the cards of two of the suits occupy the usual position or positions in the upper 20 left-hand corner, or upper left-hand and lower right-hand corner, of each card except that the usual order is reversed, the pips being placed above the value designation, while the indexes of the cards of the other 25 two suits are placed in their usual order of pip below the value designation close to the side margins of their respective cards with their value designations spaced from the top margins for a distance substantially 30 equal to that at which the value indicators of the other two suits are spaced from the top margins of their cards. In my preferred arrangement the two suits which have their 35 indexes placed in the corners are suits of contrasting colors, as therefore are also the other two suits. If cards provided with indexes in the manner hereinabove described are fanned, as shown in Fig. 1, or otherwise arranged in overlapping marginal relation, 40 the indexes of the cards of two of the suits will be aligned and the indexes of the cards of the other two suits will also be aligned, while the value designations of all the suits will be aligned. The cards of the two sets of 45 suits can readily be distinguished by the different position of their pips relative to the top margins of the cards; by selecting for the former a black suit and a red suit and doing the same for the latter, the cards of the two suits whose pips are in alignment can be 50 more readily distinguished.

It is, of course, to be understood that all

the cards of a suit have their indexes in the same relative position.

As the value indicator parts of the indexes 55 are in alignment they will, when the cards of a hand are fanned or otherwise placed in marginal overlapping relation, form to the eye a substantially continuous band which separates the pips of two of the suits from 60 the pips of the other two suits. Therefore, especially when the indexes for one of the red suits and one of the black suits are placed in the corners and the indexes of the other suits are placed away from the corners 65 as above described, the different cards of a hand may be so clearly distinguished that the arrangement thereof by suits becomes unnecessary even for an inexperienced player, thus avoiding the necessity of arranging 70 the cards according to suits and thereby quickening the play and eliminating the chance of betraying information as to features of value of the hand.

The hand shown in Fig. 1 has the pips of 75 the indexes of the two suits of major value, in a hand of bridge, disposed in the corners while the pips of the indexes of the two suits of minor value are spaced a considerable distance from the corners. A hand of 80 cards with indexes so arranged may readily be evaluated prior to bidding.

In order to make it still easier for the eye to separate the cards whose index pips are placed in the corners from the cards 85 whose index pips are placed below the value indicators, I place above and below the value indicator of each card a spacing mark, preferably a line mark as shown in Figs. 1 and 2. The marks above the value indicators 90 will, when the cards are placed in marginal overlapping relation, lie in about the same line as will also the marks placed below the value indicators and each set of marks will, when the cards of the hand are fanned as 95 shown in Fig. 1, lie in a line which constitutes approximately the arc of a circle. These two lines of spacing marks will form to the eye division indications between pips and value indicators, and, especially when they consist of short line marks as shown in the drawings, will define the edges of the continuous band hereinabove referred to 100 formed by the value indicators. These

marks will moreover assist in arranging the hand. All that need be done is to place them in alignment.

I claim:

- 5 1. A deck of playing cards, the individual cards of two suits of which are provided, in at least one corresponding corner thereof, with a pip and a value designation below the pip, such pip and designation constituting an index, and the individual cards of other two suits of which are each provided with a value designation and a pip below the same, said designation and pip constituting an index, the value designations of 10 the cards of the latter two suits being spaced from the top margins of their respective cards a distance substantially equal to that at which the value indicators on the other two suits are spaced from the top margins 15 of their cards so that when the cards are fanned the value designations form to the

eye a substantially continuous band which separates the pips of the first mentioned two suits from the pips of the last mentioned two suits.

2. A deck of playing cards as claimed in claim 1, in which the first mentioned two suits and the last mentioned two suits are each of contrasting color.

3. A deck of playing cards as claimed in claim 1 in which a spacing mark is placed immediately above each value indicator and another spacing mark is placed immediately below each value indicator.

4. A deck of playing cards as claimed in claim 1 in which a spacing mark, consisting of a short line parallel to the top edge of the card, is placed immediately above and immediately below each value indicator respectively.

CLIFFORD E. ALBERT.
